UNITED STATES PATENT OFFICE.

JOHN B. ELKIN, OF COLUMBIA, SOUTH CAROLINA, ASSIGNOR OF ONE-HALF TO JAMES H. BERRY, OF COLUMBIA, SOUTH CAROLINA.

AUTOMATIC FUSE-RESETTER.

1,082,417.

Specification of Letters Patent. Patented Dec. 23, 1913.

Application filed March 10, 1913. Serial No. 753,213.

To all whom it may concern:

Be it known that I, JOHN B. ELKIN, a citizen of the United States, and a resident of Columbia, in the county of Richland and 5 State of South Carolina, have made certain new and useful Improvements in Automatic Fuse-Resetters, of which the following is a specification.

My invention relates to improvements in 10 devices for automatically resetting fuses and it consists in the combinations, constructions, and arrangements herein described and claimed.

The main object of my invention is to 15 provide a device to be used in connection with telegraph or telephone circuits for resetting fuses which have been burned out by lightning.

A further object of my invention is to 20 provide a device for automatically resetting any number of fuses, thereby obviating the necessity of setting the device after each operation, preparatory to the next operation.

A further object of my invention is to 25 provide a novel device having certain improvements over that disclosed in my prior Patent #1,018,289.

Other objects and advantages will appear 30 in the following specification and the novel features of the device will be particularly pointed out in the appended claims.

My invention is illustrated in the accompanying drawings forming part of this application in which similar reference characters indicate like parts in the several views and in which—

Figure 1 is a plan view of the device, Fig. 2 is a view similar to Fig. 1 showing the parts in a shifted position, certain portions 40 being broken away for the sake of clearness, Fig. 3 is a side view of the device certain parts being shown in section, Fig. 4 is a section along the line 4—4 of Fig. 1, Fig. 5 is a section along the line 5—5 of Fig. 2, Fig. 45 6 is a section along the line 6—6 of Fig. 1, and Fig. 7 is a view of detail parts of the device.

In carrying out my invention I provide a base 1 upon which is mounted the binding 50 posts 2 and 3, the reel support 4, the brush supports 5 and 6 and the cleaner arm supports 7. At 8 is a casing which is secured by means of screw bolts 9, washers 10 being disposed between the casing and the base 1. 55 Journaled in the lower wall of the casing is

a shaft 10. A spring 11 has one end fastened to the shaft 10 and the other end to the wall of the casing 8. Immediately above the spring 11 is a plate or disk 12 which is secured to the hub of a ratchet wheel 13, 60 the latter being keyed to the shaft 10. Above the ratchet wheel is an escapement wheel 14, which is secured to a hub or head 15 loosely mounted on the shaft 10. The wheel 14 bears a clip 16 arranged to engage 65 the teeth of the ratchet 13. Secured to the head 15 by means of screws 17 is an insulated plate 18. This plate is of oblong shape, as shown in Figs. 1 and 2 and has mounted upon it at each end a metal block 70 19 like that shown in Figs. 5 and 7. The block is provided with a central recess 19^a arranged to receive a spring 20 (see Fig. 5). A locking plate 21 like that shown in Fig. 7 is provided with ears 22 which extend into 75 recesses 19^a of the block 19. The locking plate 21 is pivotally held to the block 19 by means of pins such as that shown at 23 in Fig. 5, which pass through the openings 22^a in the ears 22. The locking plate 21 is also 80 provided with an extension 21^b which passes through an opening 18^a in the plate 18. Carried by the casing 8 is a crescent-shaped cam 24 which is arranged to engage the extension 21^b of the plate 21 to force this part 85 toward the block 19 against the tension of the spring 20, thereby lifting the plate 21 so as to free the fuse wire 25 which the plate 21 clamps against the block 19, as will be explained later.

Referring particularly to Figs. 2 and 3, I have shown a shaft 26 which is journaled in the casing 8, and which is provided with an escapement 27 (see Fig. 2) arranged to engage the escapement wheel 14. The upper end of this shaft is provided with an arm 28, which bears at its outer extremity an insulating stop member 29. The plate 21 is provided with an opening 21^c through which the end of an S-shaped stop member 30 extends. This stop member 30 is pivotally mounted in an opening 19^a in the block 19 and the opening 21^c in the plate 21 is large enough to permit the pivotal movement of the plate 21 on its pivots 23 without interfering with the movement of the stop member 30.

As will be seen from the drawings the plate 18 has a block 19 and its associate plate 21 and stop member 30 at each end. 110

The stop member 30 is provided with an insulating tube 31 at its end arranged to engage the fuse wire 25. The fuse wire 25 is carried on a shoulder 32 mounted on the support 4. A spring 33 bears at one end on a rod 34 which passes through the post 4, as shown in Fig. 6, the outer end of a rod forming a guide eye 34^a through which the fuse wire passes. A plate 35 receives pressure from the spring 33 and the wire is held between this plate 35 and a plate 36, the latter being secured to the post by means of a thumb nut 37. The spring 33 is for the purpose of supplying sufficient tension 16 resistance to prevent the unwinding of the reel 32.

From the foregoing description of the various parts of the device the operation thereof may be readily understood.

20 In setting the device the wire is passed through the guide 34^a (see Fig. 1) and a portion of it is placed between one of the plates 21 and its associate block 19, the plate being lifted against the tension of the 25 spring 20 so that when the end of the fuse wire is placed underneath the plate it will spring down upon it and clamp it. If now the stem or shaft 10 is wound the spring 11 will be tightened. When pressure is relieved 30 from the stem 10 the spring will cause the rotation of the escapement wheel 14, which will be regulated by the escapement 27, the arm 28 vibrating to and fro. The plate 18 will rotate in the direction shown by the 35 arrows in Fig. 1. As the plate 21, opposite the end which is now gripping the fuse wire, reaches the cam 24 the engagement of the tension 21^b will open the plate to receive a portion of the fuse wire 25 when the plate 40 comes around in position to receive it. When it passes off from the cam a portion of the fuse wire will be held between two plates. As the plate revolves however that portion of the fuse wire which is held between the two plates comes in contact with the stop member 30 and pushes this stop member into the path of the insulating block 29 on the arm 28, thereby holding the arm 45 and preventing the further rotation of the 50 device since the escapement 27 cannot operate unless the arm 28 and the block 29 are in vibration. The apparatus is now set for work.

The line wires 38 and 39 are secured to 55 the binding posts 2 and 3 respectively. Current will pass from the wire 38, through binding post 2, post 5, brush 40, conducting block 19, fuse wire 25, conducting block 19 on the opposite side, brush 41, post 6, binding post 3 to wire 39. If now a rush of current such as that caused by lightning should occur the fuse wire 25 will burn out between the two clamping members 21. This will permit the block 29 which is under the tension of the escapement wheel to

vibrate back and forth, the stop member 30 being moved out of the way. The plate 18 will now rotate, and when the plate 21 which is now open passes the spring scraper or brush 42, the latter will clean out any unburned wire between the plate and the block 19. As the plate continues to revolve the wire 25 will be drawn in between the plate and the block 19 and when the extension 21^b of the plate passes off from the cam 24 the spring 20 will cause the plate to grip the wire as before described. As the fuse wire which is held between the two gripping plates 21 again comes into engagement with the stop member 30, it will be forced against the block 29 so as to stop the vibration of the latter and hence will stop the rotation of the plate. It will thus be seen that the number of fuses which may be blown in succession and immediately replaced will depend merely upon the capacity of the wire. When once set up the device requires no further attention, but is absolutely automatic and will reset the fuses as fast as they are blown out.

I claim:

1. In a device for automatically resetting fuse wires, a revoluble plate, a pair of spring clips carried by said plate and arranged to receive the wire, a spring for revolving said plate, an escapement device for regulating the movement of the plate, and means arranged to be engaged by the fuse wire for blocking the escapement, thereby stopping the rotation of the plate.

2. In a device for automatically resetting fuse wires, a revoluble plate, a pair of spring clips carried by said plate and arranged to receive the wire, a spring for revolving said plate, an escapement device having a vibrating portion for regulating the movement of the plate, a pivoted stop member carried by the fuse wire during the revolution of the plate and to be forced into the path of the vibrating portion of the escapement mechanism, thereby stopping the latter and preventing the further rotation of the plate.

3. In a device for automatically resetting fuse wires, a revoluble plate, a pair of spring clips carried by said plate and arranged to receive the wire, a spring for revolving said plate, an escapement device for regulating the movement of the plate, an arm rigidly secured to said escapement, a stop carried by said arm, said arm having a vibratory movement during the operation of the escapement mechanism, and a pivoted arm carried by the plate and arranged to be engaged by a portion of the fuse wire during the revolution of the plate and to be moved thereby into the path of the vibrating arm so as to prevent the movement of the latter, thereby stopping the rotation of the plate.

4. In a device for automatically resetting

5 fuse wires, a support, a plate revolvably mounted above said support and having openings therethrough, a pair of pivoted gripping plates for holding the fuse wires mounted on said revolvble plate, each gripping plate having a portion extending through one of the openings in said revolvble plate, and a cam disposed on said support and arranged to engage the extended 10 portions of the gripping plates successively for moving the gripping plates on their pivots.

15 5. In a device for automatically resetting fuse wires, a revolvble plate, a pair of pivoted gripping members for holding the fuse wire mounted upon said revolvble plate, means for revolving the plate, and means for cleaning the gripping members of fragments of fuse wire during the revolution of the 20 plate.

20 6. In a device for automatically resetting fuse wires, a revolvble plate, a pair of pivoted gripping members for holding the fuse

wire mounted upon said revolvble plate, means for revolving the plate, and means for 25 cleaning the gripping members of fragments of fuse wire during the revolution of the plate, said last named means comprising a scraping device having an end arranged to pass between the gripping surfaces of said 30 gripping members.

7. In a device for automatically resetting fuse wires, a base, a fuse wire reel carried thereby, a revolvble plate, a pair of gripping members carried by the plate and arranged 35 to receive the fuse wire, means for retarding the movement of the fuse wire reel, an escapement device for regulating the movement of the plate, and means arranged to be engaged by the fuse wire for blocking the 40 escapement device, thereby stopping the rotation of the plate.
